UNITED STATES PATENT OFFICE

SAMUEL JOHNSTONE, OF ALHAMBRA, CALIFORNIA, ASSIGNOR OF ONE-HALF TO
FREDERICK H. HERMAN, OF ALHAMBRA, CALIFORNIA

ARCH SUPPORTING DEVICE FOR FOOTWEAR

Application filed November 30, 1931. Serial No. 578,079.

This invention relates to and has for a purpose the provision of a device which in its association with a shoe provides a comfortable and restful support for the arch of

5 the wearer's foot so as to relieve the foot arch of undue stresses and prevent "fallen arches" as well as other foot troubles.

It is a further purpose of the invention to provide a device of the above described 10 character which may embody a cushion heel for attachment as a unit to the sole of a shoe, or may be constructed independently of the heel and separately attached to the shank of the shoe sole to function in both instances as a highly efficient support for the 15 arch of the wearer's foot.

Only two forms of this invention will be shown and described and the novel features thereof pointed out in claims.

20 In the accompanying drawing:

Figure 1 is a view showing in bottom plan a shoe with one form of arch supporting device embodying this invention applied thereto.

25 Figure 2 is a vertical longitudinal sectional view taken on the line 2-2 of Figure 1.

Figure 3 is a vertical transverse sectional view taken on the line 3-3 of Figure 1.

30 Figure 4 is a bottom plan view of a shoe with the second form of this invention applied thereto; and

Figure 5 is a vertical longitudinal sectional view taken on the line 5-5 of Figure 4.

35 Referring specifically to the drawing in which similar reference characters designate similar parts in each of the several views, and particularly to Figures 1 to 3 inclusive, this invention in its present embodiment

40 comprises an integral body designated generally at B and preferably constructed of resilient rubber or other suitable yieldable or cushioning material. The body is molded to provide a heel portion 10 having the usual

45 flat tread surface 11; and from the forward end of the heel portion 10 projects a second portion 10^a shaped to fit the shank 12 of a shoe S and of sufficient length to span the shank of the shoe sole. The portion 10^a is

50 provided with a flat tread surface 13 and is

tapered longitudinally so as to decrease in thickness toward its forward end and feather or merge into the sole of the shoe at the rear end of its tread.

The portion 10^a is bifurcated longitudinally to provide spaced apart tongues 14 and 15, the former of which is of the greater width and is disposed toward the outer side of the shoe sole. The spaced apart tongues 14 and 15 provide therebetween an intervening slot 16 which opens to the forward end of the portion 10^a and provides for the circulation of air to the shank of the shoe sole as well as permits inward displacement of the material of the tongues under pressure imposed on the latter as in walking.

The outer side edges of the tongues 14 and 15 are concave as indicated at 17 in Figure 3 for the purpose of eliminating lateral bulging of the tongues outwardly beyond the contour of the shank of the shoe sole, under pressure imposed on the tongues as in walking so that the tongues will not project beyond the shank of the shoe sole and thus be unsightly. It is to be noted that the tread 75 surface 13 of the portion 10^a is offset from the tread surface 11 of the portion 10 so as to be disposed at a slightly lower level than the tread surface 11 when the body is applied to the shoe S as shown in the drawing. The 80 portions 10 and 10^a of the body are provided at suitably spaced intervals with openings receiving conventional fastening members 18 to secure the body to the shank and heel portion of the shoe sole. In addition, a suitable 85 adhesive or cement can be employed to fixedly secure the body to the shoe.

With the body B thus applied to the shoe, it will be clear that in the act of walking the portion 10^a will come in contact with the 90 ground slightly in advance of the heel portion 10 so as to exert a yielding upward pressure upon the foot arch as well as to comfortably support the arch and relieve the latter of undue strain. That portion of the 95 body B forming the portion 10^a is preferably softer or more resilient than the portion 10 so as not to exert a harmful upward pressure on the foot arch, and should it be desired, the offsetting of the tread surfaces 100

11 and 13 can be varied as practice may dictate or can be dispensed with should the material of the portion 10^a be of the same or less resiliency than that of the heel portion 10.

5 The greater width of the tongue 14 provides for the adequate supporting of the increased weight imposed thereon due to the location of this tongue at the outer side of the shoe, as it will be evident that the weight of the 10 wearer's body is most generally thrust toward the outer side of the foot during the act of walking.

Reference will now be had to Figures 4 and 5 wherein is shown a second form of this invention constructed independently of the usual cushion heel H of the shoe and intended to be separately applied to the latter. This form of the invention comprises a body B' constructed of the same material as the 20 body B and shaped to fit the shank 12 of a shoe so as to span the shank from the forward edge of the heel H to the tread portion of the shoe sole. The body B' is tapered longitudinally so as to feather or merge at its forward end into the tread portion of the shoe sole and is bifurcated longitudinally from its forward end to form tongues 14^a and 15^a with an intervening slot 16^a identical to the 25 previously described portion 10^a of the body B. The outer side edges of the body B' are likewise concave to eliminate outward bulging of the tongues under pressure imposed thereon, and the flat tread surface 13^a of the body may or may not be offset from the tread 30 surface 11 of the heel H as practice may dictate. The body B' is secured to the shank of the shoe sole by conventional fastening members 18^a and a suitable adhesive or cement. This form of the invention functions in a manner identical to that of the 35 previously described form so as to provide a comfortable support for the foot arch to relieve the latter of undue stresses and prevent fallen arches and other foot troubles. It will 40 also be noted that by providing the arch supporting tongues 14, 15, and 14^a, 15^a of the bodies B and B' respectively, the tongues can be made to conform to shoe soles of different widths as the tongues of each form of the 45 invention can be moved towards or away from each other in applying the device to a shoe so that the outer side edges of the tongues substantially conform to the marginal contour 50 of the shank of the shoe sole.

55 I claim:

A device of the character described comprising: a body of yieldable material adapted to be secured to a shoe and having a heel portion and a portion projecting forwardly 55 therefrom, to underlie the shank of the shoe sole for the support of the foot arch, said second portion being bifurcated longitudinally from its forward extremity to provide spaced apart tongues the outer side edges of 60 which substantially conform to the marginal

contour of the shoe shank, one of said tongues being of greater width than the other to provide for greater weight imposed on the outer side of a shoe as in walking.

SAMUEL JOHNSTONE.
